UNITED STATES PATENT OFFICE

ERNEST E. SABIN, OF BEVERLY, MASSACHUSETTS, ASSIGNOR TO UNITED SHOE MANUFACTURERY CORPORATION, OF PATERSON, NEW JERSEY, A CORPORATION OF NEW JERSEY

MACHINE FOR AND METHOD OF HEEL-SEAT FITTING

Application filed March 17, 1925. Serial No. 16,222.

This invention relates to the manufacture of shoes and is illustrated as embodied in a heel seat fitting machine organized to trim surplus material from the peripheral portions of the heel seats of soles of shoes to prepare them for the attachment of wood or other similar heels.

Before attaching wood heels to shoes, it is usual to trim the surplus material from the peripheral portions of the heel seats of the soles of the shoes, at the same time beveling the heel seats to cause them to conform to the concave attaching surfaces of the wood heels. This permits the upper edges of the heels to be brought into direct contact with the material of the shoe uppers so that the sole is not visible between the heel and the upper. It is necessary that enough stock be removed from the heel seat portion of the sole to permit a tight joint between the edge of the heel and the shoe upper. At the same time it is highly desirable that no more than enough be removed. Otherwise there will be a space left between the attaching face of the heel and the heel seat portion of the shoe which will tend to weaken the shoe. The stock thus removed from the periphery of the heel seat portion of the sole is approximately of a horseshoe-shaped form, a cut or cuts being made transversely of the sole at the heel breast line to permit the complete separation from the sole of the chip or chips severed by the peripheral cut and to form an abutment against which the breast of the heel is positioned when the heel is attached.

It is an object of the present invention to improve the organization of heel seat fitting machines, particularly with respect to the operating instrumentalities of the machine which perform the actual cutting or trimming and also with respect to the parts of the machine which control the work during the trimming.

A feature of the invention comprises a drag knife and means for moving it peripherally of the heel seat of the sole of a shoe so that the trimming cut is started at one end of the heel breast line and extends rearwardly, around the heel end of the sole, and forwardly on the other side to the other end of the

heel breast line. To facilitate the trimming operation, other features of the invention comprise means for depressing the central portion of the heel seat of a sole relatively to the peripheral portion while the surplus material is trimmed therefrom by a cutter such as a drag knife traveling peripherally of the heel seat. Preferably and as illustrated herein, means is also provided, acting in opposition to the depressing means, for supporting the periphery of the heel seat of the sole during the trimming operation.

Another feature of the invention comprises a heel seat fitting machine organization in which are provided knives movable transversely of the sole to be operated upon to make the heel breast receiving cut or cuts, this organization including novel means for mounting said knives to permit the angular adjustment of the knives about a plurality of different axes so as to permit the knives to be adjusted to whatever position may be necessary to suit the requirements of the work in hand. Thus in the illustrated machine, the paths of movement of the knives for making the breast cut may be adjusted lengthwise of the sole to vary the point at which the knives enter the material of the sole, and also the paths of the knives may be angularly adjusted about a vertical axis so as to vary the angle of the heel breast receiving cuts relatively to the margin of the sole in accordance with the form of the breast of the heel to be attached. Furthermore, the knives may be tilted about an axis or axes positioned transversely of the sole so that the shoulders formed to receive the heel breast may be more or less undercut if desired.

Another object of the invention is to devise an improved method of fitting the heel seats of shoes. As illustrated herein a cut is made first at the heel breast line and the surplus material around the periphery of the heel seat of the sole is then removed by making a drag cut, starting at the first-mentioned cut and progressing around the periphery of the rear end of the sole to a similar point at the other side of the sole. In accordance with a preferred exemplification of the method the rear end of the sole is distorted to bring the

periphery thereof above the central portion and a trimming blade located in the depressed central portion of the sole cuts through the distorted periphery to the outer edge and is moved progressively around the periphery to bevel the heel seat portion.

With the above and other objects and features in view, the invention will now be described in connection with the accompanying drawings and pointed out in the claims.

In the drawings:

Fig. 1 is a perspective view, with parts broken away, of a heel seat fitting machine embodying the present invention;

Fig. 2 is a fragmentary perspective view of the support for one of the knives for making a heel breast receiving cut, showing adjusting slides;

Fig. 3 is a perspective view of the heel seat of a shoe after the heel seat fitting operation has been completed;

Fig. 4 is a vertical transverse section through the crease plates of the machine and a shoe supported therein taken through the axis of the trimming cutter;

Fig. 5 is a fragmentary perspective view illustrating the operation of the knives for making the heel breast receiving cut;

Fig. 6 is a plan view of the crease plates in which the relative horizontal position of the various cutters is illustrated and the outline of the unfitted heel seat portion of the sole of a shoe is indicated in dotted lines;

Fig. 7 shows a shoe being removed from the machine following the completion of the heel seat fitting operation, in which there was used to make the heel breast receiving cut a type of knife provided with angularly arranged cutting edges designed to make a short stiff flap beneath which the projecting end of the breast of a heel, such as a Louis heel, may be inserted; and

Fig. 8 is a diagrammatic view, with parts in section, of a shoe fitted in the fashion shown in Fig. 7, showing a wood heel attached thereto.

Referring first to Fig. 1, it will be seen that the frame of the machine comprises a substantially horizontal table 10 supported upon vertical side frames 12 which are joined by suitable braces 14 at the front and back. The central portion of the table of the machine is recessed and a substantially circular ledge is provided adjacent to said recess to receive the correspondingly shaped edges of crease plates 20. These plates are provided with grooves 24 (Fig. 6) adjacent to their edges and are held for movement along the ledge by means of a curved plate 26 having a depending rib 28 entering said groove 24. Each of the crease plates 20 is recessed and provided with a tapered projecting edge portion 30 (Figs. 4 and 7) adapted to enter the rand crease of a shoe. The recesses of the plates are so shaped that the projecting edges

meet at a point 32 (Fig. 6) located exactly at the center of the recess of the table 10 and at a point corresponding to the back seam of a shoe to be positioned by said plates. An actuating lever 34 (Fig. 1) is provided for moving the crease plates in and out so that they may be forced into the rand crease of a shoe positioned in the machine, and this lever is attached to a transverse rock shaft 36 having rock arms 38 secured thereto at 39 and linked by means of horizontal connecting members 40 to vertical studs 42 (Fig. 6) carried by the under side of the crease plates 20. A retaining latch 44 is provided to hold the lever 34 in position after the crease plates have been moved firmly into engagement in the rand crease of the shoe. Shoes to be presented to the machine are preferably mounted upon lasts and have their soles attached to their uppers. Supporting means for the last of the shoe comprise a last pin 50 resiliently and adjustably supported at the end of a swinging arm 52 pivotally mounted on a transverse shaft 54 extending between the side frames 12 of the machine. By means of this arrangement, shoes having various sizes of lasts may be adjustably mounted upon the swinging arm 52 so that the rand crease of the shoe will be in position to receive the reduced edges 30 of the adjustable crease plates as they are forced into position in said crease by means of the actuating lever 34. At the same time, it should be noted that the resilient support for the last pin 50 allows the sole to be distorted, as will later appear, by the depression of the central portion of the heel seat of the sole against the tension of the resiliently supported pin 50.

After a shoe has been positioned in the machine in the manner above outlined, power operated mechanism is set in motion to actuate the various trimming knives to perform the heel seat fitting operation. To this end a motor 60 is mounted upon the machine and is connected by suitable gears 62 to a horizontal cam shaft 64 supported in a suitable bearing 66 extending between the cross braces 14 of the machine. A one-revolution clutch, indicated at 68, may be interposed between the gears 62 and the cam shaft 64 and controlled by means of a latch 70 mounted upon a spindle 72 which is rotated to hold the latch normally in operative position by means of a spring 74. Mounted upon the outer end of this spindle 72 is an arm 76 underlying the forwardly projecting end of a latch 78 adapted to be actuated by means of a foot treadle 80 to which it is pivotally connected at 82. A spring 84 holds the latch in position for engagement with the arm 76 and a pin 86 upon the frame of the machine cooperates with a cam surface upon said latch to pull it out of engagement with the arm 76 after the clutch has been tripped in order that the clutch latch 70 may be returned

to position by the spring 74 to stop the cam shaft after it has completed one revolution.

Knives of various styles may be utilized for making the heel breast receiving cuts.

5 In the arrangement shown in Figs. 1, 2, 5 and 6, these are flat knives 90 having upright, beveled, cutting edges with the beveled portion toward the rear of the shoe. These knives are adjustably mounted upon slides 92 having racks formed upon their under sides for engagement with oscillatable pinion segments 94, said pinions being connected by means of adjustable rods 96 to bell crank levers 98 having cam rolls 100 resiliently 15 pressed by springs 99 into engagement with suitably shaped cams 102 upon the cam shaft 64. Adjustable guides are provided for the slides 92 so that, when the cam shaft is rotated, the knives will be reciprocated in predetermined paths cutting the lateral edges of the sole and forming abutments, such as are illustrated at 104 in Fig. 3, against which the breast of a heel to be attached may be positioned. As is customary in work of this 20 kind with Louis heels are to be attached to shoes, a flap 106 has been split from the heel seat portion of the sole prior to the insertion of the shoe in the heel seat fitting machine, it being understood that this flap is utilized for covering the breast of the heel after the latter has been attached. It will be evident that heels of various sizes will vary in length so that it will be necessary to adjust the position of the slides 92 in accordance with the 25 length of the heels to be handled. To this end guides 110 are mounted upon slides 112 dovetailed in the table 10 of the machine so that they may be moved forward and back along lines parallel to the longitudinal axis 30 of the sole of a shoe, and set screws 114 (Fig. 2) are provided for holding said slides in adjusted position. Aside from variations in the sizes of the heels to be accommodated, it will be evident that heels of various styles 35 may require that the paths of the breast cutting knives 90 shall be angularly adjusted about vertical axes to position the abutments 104 to coat with heels having a curved breast line. To this end the guides 110 are 40 carried by curved supporting members 116 provided with outwardly flaring edges adapted to be received in dovetailed-shaped slots 118 in slides 112 and set screws 120 are provided for retaining said curved supports 45 116 in adjusted position and to determine the angular relation of the paths of reciprocation of the knife-carrying slides 92. In addition to adjusting the angular relation of the paths of reciprocation, it may be desired to 50 tilt the cutting edges of the breast cutting knives 90 in order, for example, that the abutments 104 may be undercut to receive the forwardly extending edge of the breast 55 surface of a heel. To this end the knives are 60 adjustably supported upon the slides 92 by

mounting them upon curved plates 122 adapted to be received within correspondingly curved dovetailed slots at the ends of the slides 92. As shown in Figs. 1 and 7, the ends of slides 92 are formed of two parts 79 clamped together by screws 124, which also serve to secure plates 122 in adjusted position. The knives 90 are attached to outwardly extending arms upon the plates 122 by means of bolts 123 passing through slots 75 in the knife blades, as indicated in Fig. 1, in order that the bottom of the cutting edges may be brought down close against the upper surface of the crease plates 20. It should be noted that the curvature of the slot within 80 which the curved plate 122 is received may be about a horizontal axis substantially coincident with the plane of the upper surfaces of the crease plates 20 so that the upright edges of the knives 90 may be tilted about a horizontal axis to cause them to produce undercut abutments instead of the vertical abutments 104 illustrated in Fig. 3. The operation of these breast-cutting knives 90 is illustrated in Fig. 5, from which it will be seen that the 85 shoe is positioned in the machine by means of the crease plates 20 so that the back seam 130 coincides with the meeting point 32 of the reduced edges 30 of said plates and that said reduced edges are forced firmly into the rand 90 95 crease 132 of the shoe beneath the overhanging peripheral portion 134 of the sole. The breast-cutting knives 90 are forced inwardly from the outer edges of the sole to make cuts transversely of the sole and preferably the 100 cams 102 are so arranged that the knives act successively in order that there may be no danger that their cutting edges shall be brought into engagement with one another.

In case it is desired to fit the shoes for the reception of Louis heels in which the forward, overhanging breast of the heel tapers to a thin edge as at 136 (Fig. 8), it is helpful to provide a short, thick tongue 138 beneath the flap 106 to act as an abutment and reinforcement to aid in holding said overhanging edge 136 in position and to prevent its separation from the sole of the shoe. In this case the breast-cutting knives are formed as 105 illustrated at 901 in Fig. 7, and are L-shaped 110 in cross section so that they have not only vertical cutting edges 140 but, in addition, substantially horizontal cutting edges 142, the adjacent horizontal edge 144 being beveled to permit the free entrance of the knife into 115 the sole. When knives of the type illustrated at 901 are utilized, the curved plates 122 may be adjusted and clamped in position by means of screws 124 not only to position the vertical edges 140 of the knives but also to determine 120 the angle of severance of the short, thick tongue 138 illustrated in Figs. 7 and 8.

In addition to making the heel breast receiving cuts in the manner already indicated, the heel seat fitting operation comprises the 130

trimming of the rear end of the sole of the shoe to remove surplus material and to bevel it, as indicated at 146 in Fig. 3, in order that the upper peripheral edge of the heel, such as that shown at 148 in Fig. 8, may be brought into close contact with the upper 150 of the shoe when the heel is attached, and so that the periphery of the sole shall not show at this point. This also serves to allow the attaching face 152 of the heel 153 to be brought into close engagement with the heel seat surface 154 of the sole so that a firm support is provided for the heel by reason of the close contact between the attaching face and the heel seat of the shoe.

This trimming operation is effected by distorting the heel seat portion of the sole and rotating a knife around a fixed axis perpendicular to the sole with the cutting edge of the knife moving in a substantially horizontal plane to trim off surplus material from the periphery of the heel seat portion of the sole by cutting through the distorted edge portion. To this end, a guideway 160 is provided upon the frame of the machine at the rear and in this guideway there is mounted for vertical movement a plunger 162 having at its upper end an overhanging arm 164. A vertical stud 166 at the outer end of the overhanging arm 164 carries at its lower end a presser member 170 which is elongated as shown in the plan view in Fig. 6 and has a curved cross section as indicated in Fig. 4. The stud 166 itself is fixed in the arm 164 and serves as a bearing for a rotatable sleeve 172 having a projecting toe 174 which helps to support a flat knife blade 180 of substantially rectangular shape, as illustrated in Fig. 6, and provided with cutting edges upon the three exposed sides. Mechanism is provided for lowering the plunger 162 to bring the presser member 170 against the central portion of the heel seat of the shoe, as shown in Fig. 4, to depress said central portion below the level of the crease plates 20 so that as a result the sole is distorted and the edge portion 134 is raised above the crease plates. To this end, the resilient support for the last pin 50 allows the pressure of the presser member 170 transmitted through the wooden last 182 to depress said last pin slightly in order that the distorting action of the presser member may become effective. Whenever the breast cutting knives have been operated first, as has been previously described, the distorting action of the presser member will not only elevate the peripheral portion round the rear of the heel seat of the sole but will also elevate the peripheral portions immediately to the rear of the breast cut so that there is an abrupt projection into which the edge of the trimming knife 180 is directed as it is rotated upon the stud 166, thus facilitating the entrance of said knife into the leather of the raised edge portion of the heel seat of

the sole. The mechanism is so arranged that a single complete rotation of the trimming knife 180 is effected starting at the position illustrated in Fig. 6, after which the mechanism causes a single reverse rotation of the knife as the parts of the machine are brought back into their initial position.

To effect the depression of the plunger 162 so as to bring the presser member against the sole of the shoe a sliding bar 184 (Fig. 1) is provided having a stud 186 at its lower end entering a guide in the frame of the machine and a spring 188 surrounding said stud serves to urge the bar toward its upper position. The upper end of the bar 184 is bent to form a head 190 having a vertical spindle 192 to support and maintain in alignment a spring 194 inserted between the head portion 190 of said bar and the body portion of the plunger 162. Any motion transmitted to the sliding bar 184 is thus transmitted resiliently through spring 194 to the plunger 162 and hence to the stud 166 and presser member 170. An adjustable stop 196 is provided to limit the downward movement of the plunger so that the knife blade will never be brought into a plane below the plane of the upper surface of the crease plates. The lower end of the sliding bar 184 is slotted as indicated in dotted lines in Fig. 1, so that it surrounds the cam shaft 64 and may be power-actuated by means of a cam 198 acting against a roll 199 upon said bar.

In order to rotate the knife-carrying sleeve 172 a gear connection 200 is provided to which motion may be transmitted by means of a rack 202 carried within the overhanging arm 164 of the plunger and this rack in turn is moved by a pinion 203 carried at the upper end of a vertical shaft 204 mounted within the vertical portion of the plunger 162 and geared at its lower end to a pinion 206 mounted upon a stub shaft in the frame of the machine and arranged to be oscillated by means of a segmental gear 208 carried at the upper end of a pivoted arm 210. This arm is pivoted at its lower end on the frame of the machine and is provided with a cam roll 211 resting against a cam 212 on the cam shaft 64. A spring 214 extending between the arm 210 and the frame of the machine acts to hold the cam roll against the cam surface and to return the trimming knife to its original position at the termination of the trimming operation. Preferably, the co-ordination of the parts is such that this reverse rotation of the knife takes place after the plunger is moved upward again so that the knife is out of contact with the heel seat of the shoe.

It will be noted from Figs. 1 and 4 that a slip joint 216 is provided in the sleeve 172 carrying the knife blade. This allows for a vertical adjustment of the plane of action of the knife blade upon the supporting spindle 166 and, to hold the knife-carrying sleeve in

its adjusted relation, there is provided an adjustable plate 218 secured to the outer end of the overhanging arm 164 and projecting inwardly at its lower end between flanges 220 upon the knife-carrying sleeve 172.

5. When the operator wishes to perform the heel seat fitting operation upon any particular type of shoe he first makes sure that the stop 196 and the adjustable plate 218 are in proper adjustment and that the guides and supports for the heel breast knives 90 have been properly adjusted to move said knives in the desired path. He then places a lasted shoe upon the last pin 50 and moves the end of the shoe into the recess between the crease plates 20 and operates the lever 34 to move said plates forcibly into the rand crease thereby definitely locating the shoe in the machine and supporting the overhanging peripheral edge of the heel seat portion of the sole. 20 After this it is only necessary for the operator to depress the pedal 80 to set in motion the power-operated mechanism. This mechanism actuates the breasting knives 90 one after the other to make a transverse cut entering the peripheral edge of the sole and extending along the heel breast line so as to form an abutment such as that illustrated at 25 104 in Fig. 3. The power-operated mechanism then causes a depression of the plunger 162 forcing the presser member 170 against the central or median part of the heel seat of the shoe to distort the heel seat after which the trimming knife is rotated about its vertical axis to cut through the raised peripheral portion of the heel seat of the sole and to trim it on the bevel 146 thereby removing the surplus material and forming a properly shaped heel seat to receive the attaching surface of the heel. At the completion of a 30 single rotation of the cam shaft 64 the machine stops and the operator is enabled to release and remove the shoe.

Having described my invention, what I claim as new and desire to secure by Letters Patent of the United States is:—

1. A heel seat fitting machine comprising a work support, a knife operative to make a heel breast receiving cut in the sole of a shoe carried by the work support, a drag knife, and means for causing relative movement of the drag knife and the shoe upon the support arranged to cause the drag knife to enter the material of the sole substantially at the heel breast line to commence its trimming cut, and to continue its trimming cut peripherally around the rear of the heel seat and forwardly to complete the cut at the heel breast line on the other side of the sole. 55
2. A heel seat fitting machine comprising a work support, means for cutting heel breast receiving shoulders in a sole carried by the work support, a drag knife, and means for moving the drag knife peripherally of the heel seat of the sole arranged to

cause the knife to enter the material of the sole and commence the trimming cut substantially at the heel breast line of the sole and to move as it makes the trimming cut peripherally around the rear of the sole and forwardly to complete the cut on the other side at the heel breast line. 70

3. A heel seat fitting machine having a work support, a plurality of crease plates arranged to enter the rand crease of a shoe carried by the work support to position the shoe in the machine, a drag knife, and means for moving the drag knife peripherally of the heel seat portion of the sole of said shoe to trim surplus material therefrom starting the cut substantially at one end of the heel breast line and moving rearwardly around the end of the sole and forwardly on the other side to the heel breast line. 75

4. A heel seat fitting machine having a work support, a knife arranged for movement transversely of a shoe carried by said support to make a heel breast receiving cut at the heel breast line of the sole of the shoe, a drag knife, and means for moving said drag knife from a position forwardly of the heel breast line on one side of the shoe peripherally of the heel seat of the sole around to the heel breast line on the other side of the shoe to trim surplus stock from the sole of the 95 shoe. 85

5. A heel seat fitting machine having crease plates arranged to enter the rand crease of a shoe thereby to support the peripheral portion of the heel seat of the sole 100 of the shoe, and a drag knife operable to trim surplus material from the sole starting at one end of the heel breast line and moving around the rear of the heel seat and forward on the other side thereof to the other end of the heel breast line. 105

6. In a heel seat fitting machine, means for depressing the central portion of the heel seat of the sole of a shoe relatively to the peripheral portion thereof, and a rotatable trimming knife constructed and arranged to bevel the peripheral portion of the heel seat while thus distorted. 110

7. In a heel seat fitting machine, means for distorting the heel seat portion of the sole of a shoe, and a trimming knife rotatable about a fixed axis constructed and arranged to bevel the peripheral portion of the distorted heel seat of the sole. 115

8. In a heel seat fitting machine, a trimming knife having its cutting edge rotatable in a fixed plane, and means for presenting a shoe to said knife with the heel seat portion of its sole distorted to cause the center and the periphery of the heel seat portion of the sole to lie on opposite sides of said plane, whereby rotation of said knife will bevel the heel seat portion of said sole and trim surplus material therefrom. 120

9. In a heel seat fitting machine, crease 130

plates for supporting the peripheral portion of the heel seat of the sole of a shoe, means for depressing the central portion of said sole below the plane of the crease plates, a trimming knife having a cutting edge rotatable in a plane parallel to and just above the plane of the crease plates to remove surplus material from the periphery of the heel seat portion of the sole, and means for rotating said knife.

10. In a heel seat fitting machine, crease plates adapted to enter the rand crease of a shoe and thereby to support the periphery of the heel seat portion of the sole of the shoe, a rotatable trimming knife, and means for simultaneously depressing the central portion of said sole below the level of the crease plates and bringing the trimming knife to the plane of the crease plates, whereby the 15 rotation of said knife will remove surplus material from the periphery of the sole.

11. In a heel seat fitting machine, means for distorting the heel seat portion of the sole of a shoe to raise the peripheral portion thereof above the level of the central portion, and a trimming knife movable transversely from the forward central portion of the heel seat toward a lateral edge thereof to 25 start a trimming cut.

30. 12. In a heel seat fitting machine, a knife, means for distorting the heel seat portion of the sole of a shoe by depressing the central portion thereof and raising the peripheral portion, and means for moving said knife into the depression formed at the central portion and rotating it to cut from the center outward and then around the rear end of the sole to bevel said peripheral portion.

13. A heel seat fitting machine having 40 means for supporting the peripheral portion of the heel seat of a sole, a knife carrier, a knife supported on said carrier, a presser member mounted on said carrier and projecting beyond the knife toward a sole supported by said supporting means, means for moving said carrier and presser member toward said supporting means to distort the heel seat portion of a sole supported by said supporting means, and means for moving 45 said knife about the periphery of the distorted heel seat portion of said sole to trim surplus material therefrom.

14. In a heel seat fitting machine, means for supporting the peripheral portion of the 55 heel seat end of the sole of a shoe, a presser member for distorting the heel seat end of the sole, and a rotatable knife for trimming the periphery of the heel seat end of the sole to remove surplus material therefrom.

60. 15. In a heel seat fitting machine, a rotary trimming knife, means for moving said knife into a position such that its blade is wholly within the periphery of the heel seat portion of the sole of a shoe, and means for 65 rotating said knife from that position to

bevel the periphery of the heel seat portion of said sole.

16. In a heel seat fitting machine, a rotary trimming knife, means for moving said knife to a position within and below the periphery of the heel seat portion of the sole of a shoe, and means for rotating said knife to bevel the periphery of the heel seat portion of said sole.

17. In a heel seat fitting machine, a rotatable trimming knife, means for moving said knife into a position wholly within the periphery of the heel seat portion of the sole of a shoe, means for rotating said knife from that position to bevel the periphery thereof, and a knife movable transversely of the sole at the heel breast line to form an abutment to receive the breast of a heel to be attached to said shoe.

18. In a heel seat fitting machine, a rotatable trimming knife, means for moving said knife into a position within the periphery of the heel seat portion of the sole of a shoe, and a plurality of knives movable inwardly transversely of the sole at the heel breast line to make cuts adjoining the trimming cut made by said rotatable knife to form an abutment against which the breast of a heel to be attached may be placed.

19. In a heel seat fitting machine, a rotatable trimming knife, means for moving said knife into a position within the periphery of the heel seat portion of the sole of a shoe, a plurality of knives movable inwardly transversely of the sole at the heel breast line to make cuts adjoining the trimming cut made by said rotatable knife to form an abutment against which the breast of a heel to be attached may be placed, and means for successively moving said knives.

20. In a heel seat fitting machine, a resilient support for the last in a lasted shoe to which the sole has been attached, crease plates adapted to be received in the rand crease of said shoe to support the peripheral portion of the heel seat end of its sole, a presser member arranged to distort the heel seat portion of said sole by forcing the central part thereof from the plane of the crease plates against the tension of said resilient support, and a rotatable cutter for trimming the peripheral portion of said sole to remove surplus material therefrom.

21. In a heel seat fitting machine, a knife having an upright cutting edge movable transversely of the sole of a shoe adjacent to the heel breast line thereof to form a heel breast receiving abutment, and means for adjusting the path of movement of said knife about an axis substantially perpendicular to the plane of the heel seat portion of the sole and about another axis at right angles thereto.

22. In a heel seat fitting machine, a knife having angularly disposed edges, one of

which is arranged to make an upright cut transversely of the sole of a shoe and the other of which is adapted to make an oblique cut transversely of said sole, and means for adjusting the path of movement of said knives about an axis substantially perpendicular to the plane of the heel seat portion of the sole and about an axis substantially parallel to said heel seat portion.

23. In a machine for operating on shoe parts, a work support, a plunger movable in opposition to said work support, a presser member carried by said plunger, an adjustable stop for limiting the downward movement of the plunger, an actuating slide, means for moving said slide through a fixed range of movement, and means for resiliently connecting the slide to the plunger.

24. In a heel seat fitting machine, a work support, a vertically slidable plunger having an overhanging arm, a presser member and a rotatable cutter carried at the outer end of said arm, and power-operated means for lowering said plunger to bring the presser member and the cutter in contact with the work and for rotating said cutter to trim surplus material from the peripheral portion of the heel seat of the sole of a shoe carried by the work support.

25. In a heel seat fitting machine, a knife mounted upon a slide, means for actuating said slide to cause said knife to make a heel breast receiving cut in a sole, a guide for said slide, and means for adjusting the position of said guide to rotate the path of movement of the cutter about an axis perpendicular to the sole and to vary the point at which the cutter will enter the sole.

26. In a machine for operating on shoe parts, a work support, a slide, a bearing for said slide adjustable to rotate the path of movement of the slide about a vertical axis, means for actuating said slide, a knife mounted on said slide, and means for adjustably positioning said knife upon said slide to tilt the cutting edge of the knife around an axis parallel to the face of the work piece operated upon.

27. In a heel seat fitting machine, a manually-operated work support adapted to position the heel seat portion of the sole of a shoe in a substantially horizontal plane, and a plurality of power-operated trimming devices adapted to act successively to make overlapping cuts to remove surplus material from the peripheral portion of the heel end of said sole, one of said trimming devices being mounted for movement about a substantially vertical axis.

28. That method of fitting the heel seats of the soles of shoes for the attachment of heels which consists in making a cut approximately at right angles to the edge of a sole attached to a shoe adjacent to the heel breast line and then removing the surplus material

around the periphery of the heel seat of the sole by making a drag cut, starting at the cut made adjacent to the heel breast line and progressing peripherally of the rear end of the sole to a similar point at the other side of the sole.

29. That method of fitting the heel seats of shoes for the attachment of heels which consists in making a cut extending substantially transversely of the sole adjacent to the heel breast line, and then causing relative movement of the shoe and a trimming blade, starting at the cut made adjacent to the heel breast line and progressing peripherally of the rear end of the sole to a similar point at the other side of the sole.

30. That method of fitting the heel seats of shoes for the attachment of heels which consists in distorting the peripheral portion of the heel seat of a sole, making a cut transversely of the sole through the distorted portion adjacent to the heel breast line, causing a trimming blade to enter the periphery of the sole at said cut, and moving it peripherally of the rear end of the sole to a corresponding point upon the other side of the sole thereby to remove surplus material.

31. That method of fitting the heel seats of shoes for the attachment of heels by trimming surplus material from the periphery of the rear end of a sole which consists in distorting the rear end of the sole to bring the periphery thereof above the central portion, and causing relative movement of the shoe and a trimming blade to make a cut, starting within the periphery and progressing thence toward the outer edge and around the periphery to bevel the heel seat portion of the sole.

32. In a heel-seat fitting machine, a support for a shoe, crease plates arranged to enter the rand crease of a shoe on the support, means for beveling the peripheral portion of the heel-seat of the sole of a shoe carried by said support and having its rand crease engaged by said crease plates comprising a drag-knife, and power-operated means for producing relative arcuate movement of the work support and the drag-knife in a path determined by the machine and irrespective of the form of the work to effect the beveling action.

33. A heel-seat fitting machine having a work support, a drag-knife, and power-operated means for rotating the drag-knife in a fixed path and about a fixed axis to remove surplus material from the edge of the heel-seat of the sole of a shoe carried by said work support.

34. A heel-seat fitting machine having a plurality of crease plates arranged to enter the rand crease of a shoe to position the periphery of the heel-seat portion of the sole thereof in the machine, a drag-knife, and power-operated means for moving said drag-

knife about the periphery of the heel-seat portion of the sole of said shoe to trim surplus material therefrom.

35. A heel seat fitting machine having, in combination, a work support, an arm arranged to overhang a shoe supported sole upwardly upon the support, and a cutter carried by said arm and arranged for arcuate movement about an axis substantially at right angles to the sole of a shoe on said support thereby to operate upon the peripheral portion of the heel-seat of the sole of the shoe upon the support and to perform a portion of the heel seat fitting operation.

36. A heel seat fitting machine having, in combination, a work support, a plurality of relatively movable crease plates arranged to enter the rand crease of a shoe carried by the support to position the shoe in the machine and to support the periphery of the heel-seat portion of its sole, an arm arranged to overhang the sole of a shoe thus positioned, and a cutter carried by the arm and arranged to operate peripherally about the heel-seat of the sole of the shoe from one breast corner rearwardly, then around the rear end of the heel-seat and forwardly to the other breast corner and thereby to perform a portion of the heel seat fitting operation.

37. A heel seat fitting machine having, in combination, a work support, a pair of crease plates arranged to enter the rand crease of a shoe carried thereby and mounted for arcuate adjustment about a point substantially in alinement with the back-seam of a shoe carried by the work support, an arm arranged to overhang the sole of a shoe carried by the work support, a shaft carried by said arm, means for rotating said shaft, and a cutter operatively connected to said shaft and caused by the rotation of the shaft to remove stock from the peripheral portion of the sole of the shoe carried by said support thereby by performing a portion of the heel seat fitting operation.

38. A heel seat fitting machine having, in combination, a work support, a cutter support arranged to overhang a shoe supported sole upwardly upon the work support, and a cutter carried by the outer end of said cutter support and arranged for arcuate movement peripherally of the heel-seat of the sole of a shoe carried by the support thereby to trim surplus material from the sole of the shoe and to perform a portion of the heel seat fitting operation.

39. A heel seat fitting machine having, in combination, a work support, a plurality of crease plates arranged to enter the rand crease of a shoe carried thereby, a knife support arranged to overhang the sole of a shoe carried by the work support, a vertical shaft carried by said support, means for rotating said shaft, and a drag-knife operatively connected to said shaft and caused by the rota-

tion of the shaft to remove stock from the sole of a shoe and perform a portion of the heel seat fitting operation.

40. A heel-seat fitting machine having, in combination, means for supporting the peripheral portion of the heel-seat of a sole, a spring-pressed plunger, means for causing relative movement of the plunger and the supporting means to distort the peripheral portion of the heel-seat of the sole, a pair of knives, and means for moving said knives transversely of the sole and towards each other to cause the knives to form heel-breast-receiving abutments substantially at the heel-breast line of a sole upon the support and distorted by the plunger.

41. A heel-seat fitting machine having, in combination, means for supporting the peripheral portion of the heel-seat of a sole, a member arranged to engage the median portion of the heel-seat of a sole upon the support and, by pressure against the sole, to distort the peripheral portion of its heel-seat, and a knife movable transversely of the sole from its edge substantially at the heel-breast line inwardly to cut a heel-breast-receiving abutment in the sole, said knife being mounted for adjustment to vary the angular relation of its cutting edge to the surface of the sole.

42. A heel-seat fitting machine having, in combination, means for supporting the peripheral portion of the heel-seat of a sole, a spring-pressed member arranged to engage the median portion of the heel-seat of a sole upon the support and, by pressure against the sole, to distort the peripheral portion of its heel-seat, and a knife movable transversely of the sole from its edge substantially at the heel-breast line inwardly to cut a heel-breast-receiving abutment in the sole, said knife being mounted for adjustment to vary the angle of its path of movement relatively to the edge of the sole.

43. A heel-seat fitting machine having, in combination, means for supporting the peripheral portion of the heel-seat of a sole, a spring-pressed plunger, a member operated thereby and arranged to engage the median portion of the heel-seat of a sole upon the support and, by pressure against the sole, to distort the peripheral portion of its heel-seat, and a knife movable transversely of the sole from its edge substantially at the heel-breast line inwardly to cut a heel-breast-receiving abutment in the sole, said knife being mounted for adjustment to vary the angular relation of its cutting edge to the surface of the sole and the angle of its path of movement relatively to the edge of the sole.

44. A heel seat fitting machine having, in combination, a frame, a form plate, a plunger, said form plate and plunger being arranged for relative movement to deform and hold the heel end of a shoe sole, a splitting knife,

and a pair of severing cutters, the knife and the cutters being arranged for movement in intersecting paths in the plane of the shoe sole.

5. 45. A heel seat fitting machine having, in combination, means to deform and to hold the heel end of a shoe sole, means to split said end into a central and a marginal part, and a pair of severing cutters arranged for movement towards each other in the plane of the sole.

10 46. A heel seat fitting machine having, in combination, means to split the heel end of a shoe sole into central and marginal parts, and a pair of severing cutters arranged for movement in the plane of the sole.

15 47. A heel seat fitting machine having, in combination, means to split the heel end of a shoe sole into central and marginal parts, a pair of severing cutters arranged for movement from the sides toward the centre of the sole, and means for regulating the angle of said cutters in relation to the plane of the sole.

20 48. A heel seat fitting machine having, in combination, means to split the heel end of a shoe sole into central and marginal parts, a pair of severing cutters arranged for movement from the sides towards the longitudinal median line of the sole, and means for determining the angle in relation to said line that the cutters are moved.

25 49. A heel seat fitting machine having, in combination, a frame, means to split the heel end of a shoe sole into central and marginal parts, bearings supported by said frame and located on opposite sides of the sole, members supported by said bearings and arranged for movement towards and from each other, and severing cutters on the adjacent ends of said members.

30 50. A heel seat fitting machine having, in combination, a frame, means to split the heel end of a shoe sole into central and marginal parts, bearings supported by and arranged for adjustment relatively to said frame, members supported by said bearings and arranged for movement towards and from each other, severing cutters on said members, and means whereby movement is imparted to said members.

35 51. A heel seat fitting machine having, in combination, means to split the heel end of a shoe sole into central and marginal parts, a pair of severing cutters, and means for imparting movement to said cutters in the plane of the sole.

40 52. In a machine of the class defined having means to split the heel end of a shoe sole into central and marginal parts, a pair of severing and shouldering cutters arranged for movement in the plane of the sole, and means to determine the direction of movement of said cutters in said plane.

45 53. In a machine of the class defined having

means to split the heel end of a shoe sole into central and marginal parts, a pair of severing and shouldering cutters arranged for movement in the plane of the sole, means to determine the direction of movement of said cutters in said plane, and other means to determine the angular disposition of the cutters in relation to said plane.

5. 70 75 45. A heel seat fitting machine having in combination, a splitting knife arranged for movement in a plane, and a pair of severing cutters arranged for movement towards and from each other in said plane in a direction transverse to the direction of movement of the splitting knife.

75 80 85 55. A heel seat fitting machine having, in combination, a frame, means to deform the heel end of a shoe sole attached except at the heel end and to a shoe, means to locate the heel end and the forepart of the shoe, and a splitting knife and severing cutters arranged for movement in a single plane.

85 90 95 56. A heel-seat fitting machine having, in combination, power-operated means to split the heel end of a shoe sole into central and marginal parts, and a pair of power-operated severing cutters arranged for movement in the plane of the sole.

100 95 100 57. A heel-seat fitting machine having, in combination, means to deform and to hold the heel end of a shoe sole, power-operated means to split said end into a central and a marginal part, and a pair of power-operated cutters arranged for movement toward each other in the plane of the sole.

105 100 105 58. A heel-seat fitting machine having, in combination, power-operated means for deforming and holding the heel end of a shoe sole, a power-operated cutter to split said end into a central and a marginal part, and a pair of power-operated severing cutters arranged for movement toward each other in the plane of the sole.

110 110 115 59. A heel-seat fitting machine having, in combination, a shoe support, a drag knife, means for moving the drag knife peripherally of the heel seat of a sole of a shoe upon said support constructed and arranged to cause the knife to enter the material of the sole and to commence a trimming cut substantially at one side of the breast line of the sole and to move as it makes the trimming cut peripherally around the rear of the sole and forwardly to complete the cut at the other side of the heel-breast line of the sole, and cutters arranged at opposite sides of the sole and mounted for movement toward each other in the plane of the sole, said knife and said cutters being arranged in intersecting paths.

120 115 120 125 60. In a heel-seat fitting machine, a trimming knife having its cutting edge rotatably mounted in a fixed plane, means for presenting a shoe to said knife with the heel-seat portion of its sole distorted to cause the center

- and the periphery of the heel-seat portion of the sole to lie on opposite sides of said plane whereby rotation of said knife will bevel the heel-seat portion of said sole and trim surplus material therefrom, a pair of severing cutters arranged for movement toward the median line of the sole of the shoe, and means for determining the angle in relation to said line at which the cutters are moved.
61. A heel-seat fitting machine having, in combination, means to split the heel end of a shoe sole into central and marginal parts, a pair of power-operated severing cutters arranged for movement in the plane of the sole, means for determining the direction of movement of said cutters in said plane, and other means to determine the angular disposition of the cutters in relation to said plane.
62. A heel-seat fitting machine having, in combination, means for positioning a shoe, a cutter constructed and arranged to operate upon the rear portion of the sole of the shoe to form a reduced heel-seat portion thereof shaped to fit within a concave attaching face of a heel, means for forming a heel-breast-receiving abutment upon the sole, and power-operated means for moving the cutter peripherally at the heel-seat of the sole of the shoe positioned by said means, from one end of the heel-breast line of the sole rearwardly and then forwardly to the other end of the heel-breast line, to trim surplus material from the periphery of the heel-seat portion of the sole.
63. A heel-seat fitting machine having, in combination, a support for a shoe, a cutter carrier, a cutter carried thereby and constructed and arranged to operate upon the rear portion of the sole of the shoe to form a reduced heel-seat portion thereof shaped to fit within a concave attaching face of a heel, means for forming a heel-breast-receiving abutment upon the sole, and power-operated means for moving the cutter carrier and the cutter peripherally of the heel-seat of the sole of the shoe carried by the support from one end of the heel-breast line rearwardly and then forwardly to the other end of the heel-breast line, to trim surplus material from and to bevel the periphery of the heel-seat portion of the sole.
64. A heel-seat fitting machine having, in combination, a support for a shoe, crease plates arranged to enter the rand crease of a shoe carried by the support, a cutter carrier, a cutter carried thereby, and power-operated means for moving the cutter carrier and the cutter peripherally of the heel-seat of the sole of the shoe carried by the support and the rand crease of which is engaged by the crease plates to trim surplus material from and to bevel the periphery of the heel-seat portion of the sole of the shoe.
65. A heel-seat fitting machine having, in

combination, a support for a shoe, a hold-down member arranged to engage the central portion of the heel-seat of the sole of a shoe carried by the support, and a cutter mounted for movement peripherally about the heel-seat of the shoe and formed and arranged to trim surplus material from and to bevel the heel-seat portion of the sole.

66. A heel-seat fitting machine having, in combination, a support for a shoe, a hold-down member arranged to engage the heel-seat of the sole of a shoe carried by the support, a cutter arranged for movement peripherally of the heel-seat portion of the sole of the shoe while the hold-down member is in engagement therewith to trim surplus material from the sole, and a cutter constructed and arranged to form a heel-breast-receiving abutment on the sole.

67. A heel-seat fitting machine having, in combination, a support for a shoe, means arranged to engage the sole of a shoe carried by the support to prevent displacement thereof, a cutter formed and arranged for movement peripherally of the heel-seat portion of the sole of a shoe to trim surplus material therefrom, and a cutter constructed and arranged to form a heel-breast-receiving abutment on the sole.

In testimony whereof I have signed my name to this specification.

ERNEST E. SABIN.
